BATHROOM ARTICLE HOLDER

Gustav A. Hallenscheid, Los Angeles, Calif., assignor to Hall-Mack Company, Los Angeles, Calif., a corporation of California

Application March 8, 1949, Serial No. 80,253

5 Claims. (Cl. 312—342)

1

The present invention relates to bathroom fixtures, and more particularly to a bathroom article holder, wherein an article supporting portion thereof is removable for cleaning.

The art pertaining to bathroom fixtures is a crowded one, and the makers of this type of equipment have made numerous changes and improvements in their products during recent years. This development has been stimulated by the tremendous increase in residence building. Fixtures of chrome and plastic combinations have been very popular, since their brightness and ease of cleaning adds greatly to the appearance of a bathroom. One fixture which has not been satisfactorily designed in such a combination is a soap dish or tumbler holder. In the case of such a fixture it is desirable that it fit into a relatively shallow recess in the wall in which it is to be installed. Previous attempts to design such a fixture have resulted either in an arrangement where a metal shelf projected from a recessed wall plate, which added to the cost of manufacture and made it more difficult to clean, or where a forwardly projecting plastic insert was used, in which case the insert either became jammed in place by an accretion of soap deposit or fell out when the soap or other article became stuck to the insert or was placed too close to its projecting forward edge.

An object of the present invention is to make an improved combination article holding bathroom fixture.

Another object is to make an improved article holding bathroom fixture with demountable article support portions.

Another object is to make a bathroom fixture with a recessed housing and easily detachable interlocking article support portions.

In order to attain these objects there is provided in accordance with one feature of the invention a metal recessed housing adapted for mounting over a hole in a wall, the housing having a pair of inwardly projecting studs and a removable plastic article support adapted to be inserted in the housing recess and to project forwardly therefrom.

The present invention contemplates the provision of an article support having a substantially rectangular frame section formed with a semi-cylindrical vertical recess, the end walls of which are horizontal, the said recess being provided to accommodate an article to be supported and receiving an article supporting member detachably secured in position and interlocking in a manner to prevent tilting of the article support.

2

The invention is illustrated by way of example in the accompanying drawing in which:

Figure 1 is a view in perspective showing an article holding fixture embodying the present invention mounted on a wall.

Fig. 2 is a sectional view taken in the plane of the line 2—2 of Fig. 1 and shows the relationship of the holder and the demountable member.

Fig. 3 is an enlarged fragmentary view in vertical section taken in the plane of the line 3—3 of Fig. 2 and shows the connection between the insert and the housing.

Fig. 4 is a fragmentary view in central vertical section showing a modified form of the invention.

Fig. 5 is a fragmentary view in central vertical section showing another modification of the present invention.

In the illustrated embodiment of the invention a housing 10 is made of sheet or cast metal, such as brass, steel, or die casting metal, and comprises a rectangular frame portion 11 and a semi-cylindrical recessed portion 12. The entire exposed face of the housing preferably is provided with an attractive finish such as chrome or other tarnish-resistant plating, or enamel. The housing is adapted to be mounted with the portion 12 inserted in a hole or recess provided in a wall 16, as shown in Fig. 2. The frame portion 11 is in contact with the face of the wall so as to conceal the edges of the wall opening. The housing may be secured in position as shown in Fig. 2, where a wooden header 13 is mounted transversely between adjacent studdings 13a on opposite sides of the wall opening. The header is spaced inwardly from the face of the wall a distance sufficient to permit the rear of the housing to be secured to the header by screws 14, with the frame 11 in position against the face of the wall. In the case of masonry walls a seat of plaster or other suitable adhesive may be mounted in the wall opening and the housing 10 pressed into position in the material so as to be seated therein; when intended for setting in such material the rear face of the semicylindrical portion 12 of the housing preferably is provided with roughened areas or with projections of a usual sort to extend into the material and increase the adhesion of the material with the housing.

A pair of studs 15 is mounted one on each side of the semicylindrical portion 12 of the housing to project inwardly therefrom, as best shown in Fig. 3. An article supporting insert 17 is molded preferably of a clear transparent substance such as an acrylic resin. The insert member has a

semi-circular rear face adapted to be inserted in, and to conform to the curvature of, the semi-cylindrical portion 12 of the housing. The insert 17 has an upwardly extending circularly curved rear marginal wall 18 molded integrally with the body of the insert and adapted to conform closely to the curved wall of the recess. The forward end portions of the wall 18 are of a thickness somewhat greater than the length of the studs 15, and are each provided with vertical grooved channels 19, as shown in Fig. 3, adapted to receive the studs 15 when the insert 17 is inserted into the recess above the level of the studs 15 and then moved slidably downward over them. The forward portion 20 of the insert 17 is of a length to extend forwardly beyond the face of the rectangular frame portion 11 of the housing. The entire upper surface of the insert 17 may be molded to form a continuous planiform surface, as illustrated, so that the device can be used for holding soap or a tumbler interchangeably; or if desired, may be given any of the usual special conformations where the holder is to be used only for holding a tumbler, or soap, as the case may be.

The portion 20 of the base which projects forwardly from the rectangular frame portion 11 is thicker than the portion within the recess 12 of the housing and has a downward step or offset portion 21 (see Fig. 2), to engage and form an interlock with frame 11 below the recess 12. This interlock, together with the engagement of the studs 15 with the sides of their respective receiving channels 19, resists downward stresses on the forwardly projecting portion 20 of the support area of the insert. This resistance to such stresses increases in proportion to increase in the stresses.

In the use of the present structure the housing is suitably mounted within a hole or recess in a building wall by the screws 14, and is disposed so that the semi-circular recess 12 will be vertically positioned. The studs will be positioned adjacent the lower horizontal face of the recess and will be at opposite sides thereof. The article support may then be slipped into the recess so that its arcuate wall 18 will conform to the contour of the recess, and its lower face will rest upon the horizontal lower wall of the frame. The slotted openings 19 of the article support 17 are then placed in register with the studs 15 and the article support is moved downwardly until it rests upon the bottom face of the semi-circular recess. At this time the overhanging portion 20 of the article support 17 will be disposed so that its shoulder or offset portion 21 will rest against the front face of the frame 11. By reference to Fig. 2 it will be evident that this plane of contact is considerably below the points of engagement of the studs 15 with the slots 19. Thus any weight which is disposed upon the overhanging portion 20 will tend to cause the studs 15 to interlock with the slots 19 and to prevent the article support from being dislodged. In fact, the weight of a tumbler or the like disposed on the upper horizontal face of the article support 17 will tend to cause the article support to be held in position and any over-balancing weight imposed upon the overhanging portion 20 will act to hold the article support more firmly.

It will be obvious that in the construction here disclosed the cooperation of the studs 15 and the offset shoulder portion 21 will act to hold the article support in position regardless of whether or not any weight is imposed upon it. Due to this construction it is not necessary to provide

any complicated attaching means or any means which might become coated or corroded. For this reason the article support may be easily lifted upwardly in the recess so that the studs 15 will not be in engagement with the slotted recesses 19, thus allowing the support to be easily removed and cleaned, and replaced when desired.

By reference to Fig. 4 of the drawings it will be seen that a protrusion 22 is formed on the rear semi-cylindrical wall 16 of the housing 12. This is in a plane to be occupied by the upper edge or face of the article supporting insert 17. This construction embodies an alternate form of the invention so that the upper edge of the insert 17 may be placed beneath the protrusion and will cooperate with the studs 15 and their slots 19 to hold the insert in position in the same manner as would be accomplished by the shoulder 21.

Referring more particularly to Fig. 5 of the drawings it will be seen that the insert 17 is formed as previously described with a shoulder 21 which rests against the front face of the frame 11. In this particular device the use of slots 19 and the studs 15 is eliminated and in place thereof a hook 23 is secured to the back wall of the housing and projects forwardly to overhang the arcuate wall 18 of the insert 17. In this device a shoulder 21 and the hook 23 cooperate to secure the insert 17 detachably and make it possible for the insert to be easily tilted and lifted from the housing and moved to a position of disengagement with the hook 23.

It will thus be seen that the invention here disclosed is simple in construction and will insure that the mounting member may be easily detached and removed.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. An article holding bathroom fixture having a housing adapted to be mounted on a building wall, said fixture having a forwardly exposed recess therein, a stud mounted on a side of the recessed portion of said housing to project into said recess, an article supporting insert member having a rear face thereof adapted to enter and substantially to conform with the portion of said fixture defining the rear wall of said recess, said insert member being adapted to seat upon the portion of the housing defining the lower end of said recess, said insert member having a vertically disposed channel therein adapted to receive said stud upon moving said insert member downwardly into seated position upon the lower end of said recess, said insert member having a forward portion adapted to project forwardly beyond said housing when inserted therein, and said forward portion having a downwardly extending offset portion adapted to overlie and have interlocking engagement with a forward marginal portion of said housing defining the lower edge of said recess.
2. An article holding bathroom fixture adapted to be mounted in a wall opening, said fixture having a housing with a marginal frame portion and a central forwardly exposed recessed portion, a stud mounted on each side of the recessed portion of said housing to project into the recessed portion, an article supporting insert member adapted to enter and substantially

- 70

to conform with the lower end of said recessed portion, said insert having a vertically disposed channel in each side thereof adapted to receive said studs on moving said insert downwardly into seated position on the lower end of said recess, said insert member having a forward portion adapted to project forwardly beyond said housing when inserted therein, and said forward portion having a downwardly extending offset portion adapted to overlie and have interlocking engagement with said frame portion below the recessed portion of said housing.

3. An article holding bathroom fixture comprising a metallic housing having a forwardly recessed thin walled portion of semicylindrical shape adapted to be mounted in an opening of conforming shape and size in a building wall with the cylindrical axis vertical, a marginal frame portion unitary with the recessed portion adapted to lie against the building wall to cover and conceal the edges of the wall opening in which the recessed portion is mounted, a molded plastic article supporting insert adapted to be inserted in said recessed portion to lie adjacent the lower end thereof, said insert having a rear edge thereof curved to conform to the wall of the recessed portion, a rear marginal wall formed integrally with the insert and curved to conform to the curvature of the wall of the recessed portion, said insert having a vertical groove in each side thereof extending from the lower side of said insert up into the wall portion thereof, a pair of lugs mounted above the lower end of said recessed portion to project inwardly into the recessed portion to enter said grooves, a forwardly extending portion formed integrally with said insert and having its upper surface co-extensive with that of the remainder of the insert other than said wall, and a downwardly offset step portion formed integrally with said forwardly extending portion and adapted to overlie and have interlocking engagement with the frame portion of said housing below the level of said studs to resist downward pressure on the forwardly extending portion of said insert.

45

4. The structure of claim 3 wherein the offset step portion is formed by a substantial thickening of the forwardly extending portion of the insert.

5. An article holding bathroom fixture comprising a housing having a forwardly opening semicylindrical recessed portion therein adapted to be mounted with the cylinder axis vertical in a conforming opening in a building wall, said housing having an inwardly projecting member on each side and spaced upwardly from the lower end of said recessed portion, a molded, easily cleaned decorative insert with flat upper surface adapted to be inserted into the recess to conform with the lower end thereof, said insert having substantially vertical upwardly extending grooves therein adapted to receive the inwardly projecting members on a downward movement of said insert from an elevated position in said recess, the forward portion of said insert when mounted in said recess being of a length to project forwardly beyond said housing to extend the article supporting area thereof, and a downwardly projecting element on the under side of said forward portion adapted to overlie the lower front margin of said recessed portion below the level of said inwardly projecting members, thereby to resist pivotal movement of the insert about said latter members when downward stresses are applied to the projecting forward end of said insert.
